UNITED STATES PATENT OFFICE.

LILLIE McGRATH, OF CHICAGO, ILLINOIS, ASSIGNOR TO MARSHALL FIELD & COMPANY,
OF CHICAGO, ILLINOIS, A CORPORATION OF ILLINOIS.

HAIR-NET.

1,176,155.

Specification of Letters Patent. Patented Mar. 21, 1916.

Application filed February 13, 1915. Serial No. 8,121.

To all whom it may concern:

Be it known that I, LILLIE McGRATH, a citizen of the United States, residing at Chicago, in the county of Cook and State of Illinois, have invented certain new and useful Improvements in Hair-Nets, of which the following is a specification.

This invention relates to a hair net of novel construction, which effectively prevents disarrangement of the hair, and which cannot be easily distinguished from the hair of the wearer.

It has been observed that human hair is almost uniformly wavy, curly, or crimped in some degree, and for this reason the usual hair net formed of straight strands of hair or silk will not perfectly adapt itself to the contour of the coiffures and is capable of being readily detected.

My invention therefore contemplates the construction of a hair net composed of strands of hair, silk, or other suitable material, which are given a substantially permanent crimp, curl or wave so that the meshes of the net can adequately adapt themselves to the hair of the coiffure, and the strands of the net are not readily distinguishable, owing to their similarity to the natural human hair. These and other features of my invention will be more particularly set forth in connection with the following description and accompanying drawings, in which I have illustrated and described a particular form of my invention.

In the drawings; Figure 1 shows an end portion of my improved hair net when the same is closed or folded; Fig. 2 shows a view of the same when it is in a partially open position with the strands spread apart; Fig. 3 shows one method of embodying my invention in a hair net; Fig. 4 shows a portion of the hair net which has been treated in the manner shown in Fig. 3 when the same is closed or folded; and Fig. 5 shows the same hair net in a partially open position with the strands spread apart.

Referring to the drawings, I have shown my improved hair net 10 as comprising a plurality of interwoven strands 11, having their ends drawn together and knotted, or otherwise secured, as shown at 12. The net may be formed in any suitable manner from strands of hair, silk, or other suitable material, and after constructing the net, for

example, in the form shown in Fig. 2, the extremities 12 thereof are drawn apart until the net is elongated into a relatively narrow band. The net is then treated by any suitable means to introduce a series of crimps, 60 curls or waves into the strands of which it is composed. These waves, curls or crimps are indicated in the drawings by the elevations 13 and depressions 14 succeeding each other longitudinally of each strand. In 65 some instances, especially when the net is formed from strands of silk, it is preferable to weave a long strip or band of interwoven strands, which strip is crimped, curled or made wavy in one operation, and then cut 70 up into sections of suitable length to form nets for the hair, after which the ends of said sections are knotted or otherwise treated to mutually secure the ends of the strands. After the crimping operation the net will, 75 upon being spread apart, have a general appearance similar to that shown in Fig. 2.

In Fig. 3 I have illustrated one method of embodying my invention in a hair net which consists in providing a cylinder 15 80 such, for instance, as a cardboard tube upon which the hair net is wound in order to impart to it the desired undulating appearance. The tab or ear 16 is cut from the tube 15 and the central portions 17 of the hair net 85 engage therewith. The portions of the hair net on opposite sides of the central portion are then wound about the tube 15, as indicated at 17¹ and 17². After the hair net has remained in its wound condition upon the 90 tube 15 for a sufficiently long time to permanently impart to it an undulatory form, it is unwound therefrom and then has an appearance substantially such as shown in Fig. 4 before the strands are spread apart. When 95 the strands are spread apart the hair net has substantially the appearance shown in Fig. 5, in which the central portion 17 is adapted to overlie the part of the hair of the wearer, and hence is not undulatory. The center of one side edge of the net, in this form of my invention, is curved inwardly, as shown in Fig. 5, which central portion is adapted to be located at the front of the part of the hair with the projecting portions of each side 100 thereof overlying the hair on opposite sides of the part.

It will be seen that a net for the hair constructed in accordance with this invention will closely resemble the natural human hair 110

on the head of the wearer, and that the use of one of these nets of the proper color shade cannot be readily detected. Furthermore, owing to the undulations in the net, it so readily adapts itself to the contour of the wearer's hair as to more effectively hold the same in the desired orderly arrangement.

It may be desirable to introduce crimps of varying amplitude and wave lengths into 10 the strands of the net in order that various parts thereof will more perfectly match the hair on different portions of the wearer's head.

It will be understood that my invention is 15 applicable to any form of hair net, and that various changes in form and method of formation may be made without departing from the spirit of my invention as embodied in the appended claims.

20 While in the claims hereto attached I have used the term undulatory to designate the appearance, or form of my improved hair net, yet it will be understood that such term is used generically and includes a crimped, 25 curled, waved or any other undulatory form or appearance.

Copies of this patent may be obtained for five cents each, by addressing the "Commissioner of Patents, Washington, D. C."

I claim:

1. A net for the hair comprising a plurality of strands having artificial undulations resembling the natural undulations of 20 human hair.

2. A net for the hair composed of interwoven strands having artificial undulations resembling the natural undulations of 35 human hair.

3. A net for the hair comprising interwoven strands, said strands having artificial undulations to resemble human hair.

4. A net for the hair comprising interwoven strands, the portions of said strands 40 forming the transverse central portion of the net being straight, and the portions of said strands on opposite sides of said central portion having artificial undulations to resemble the natural undulations of human 45 hair.

In testimony whereof I have subscribed my name.

LILLIE McGRAH.
